UNITED STATES PATENT OFFICE.

CHARLES W. LEE, OF LOCK HAVEN, PENNSYLVANIA.

COMPOSITE REINFORCED RAILWAY TIE.

Application filed January 13, 1927. Serial No. 160,880.

The invention relates to railway ties and has for its principal object the provision of a tie that will replace the wooden ties now commonly used and that will add to the 5 length of life of railway ties, avoiding replacement, and at the same time will have the advantages of a wooden tie in providing a tie that would include a wooden support for the rail enclosed within a reinforced 10 plastic shell, the wooden support for the rail contributing a cushion effect of the wooden tie, and the reinforced plastic shell preventing the contact of the wooden portion with the ground and the consequent disintegration 15 thereof.

Another object of the invention is the provision of a railway tie made up of the plastic shell and the wooden insert, reinforcing means for the plastic shell being secured 20 to the wooden insert to provide a homogeneous structure.

A further object of the invention is the provision of a composite railway tie comprising a shell of plastic material and a 25 wooden insert with reinforcing means for the plastic shell comprising a frame surrounding the wooden insert and including members located under the bottom of the wooden insert and having angular extensions secured to the ends of the portion surrounding the insert.

The invention will be described in detail hereinafter and will be found illustrated in the accompanying drawings in which

35 Figure 1 is a top plan view of a railway tie made in accordance with the invention,

Figure 2 is a longitudinal sectional view on a plane indicated by the line 2—2 of Figure 1,

40 Figure 3 a transverse sectional view on a plane indicated by the line 3—3 of Figure 1, and

Figure 4 a horizontal sectional view on a plane indicated by the line 4—4 of Figure 2.

45 In the drawings similar reference characters will be used to designate corresponding parts throughout the several views.

The improved railway tie comprises a shell 1 preferably of plastic material such 50 for instance as concrete, glass or any other

suitable material having embedded in the upper face thereof an elongated block of fibrous material, preferably wood, designated 2, and of sufficient length to receive the spaced rails of a railway track. The 55 shell 1 is reinforced by means of a reinforcing member generally designated 3, and consisting of a rectangular frame member 4 enclosing the sides and ends of the block 2 and bolted or otherwise secured thereto as 60 shown at 5, and one or more rods 6 arranged under the block 2 and having upturned ends 7 secured to the ends of the frame 4. The reinforcing member 3 is preferably 65 made of spirally twisted rods as shown in the drawing to insure intimate engagement of the reinforcing member 3 with the plastic material in casting the tie.

It will be understood that in making the tie the reinforcing member 3 is secured to 70 the wooden block 2 by the fastening members 5 and the block and reinforcing member are then arranged in a mold into which the plastic material is placed which envelopes the sides and ends and bottom of the 75 block 2 and encloses the reinforcing member 3, so that when the plastic material hardens a composite tie is provided having a shell 1, as heretofore described, enclosing and supporting the block 2, and when in 80 position under the rails the block 2 by supporting the rails provides a cushion support therefor, and as the shell 1 protects the sides and ends and the bottom of the block 2 from the weather and contact with the ground, the 85 life of the tie will be considerably prolonged.

What is claimed is:—

A railway tie, comprising a block of 90 fibrous material extending longitudinally of the tie and terminating adjacent to the ends thereof, a shell of plastic material enclosing the ends, sides and bottom of the block and constituting therewith the tie aforesaid, a reinforcing element for the shell, comprising a 95 rectangular frame surrounding the block and secured thereto, and a rod located under the block and having upturned ends engaging the ends of the frame.

In testimony whereof I affix my signature.
CHARLES W. LEE.
